UNITED STATES PATENT OFFICE.

WILLIAM A. GIBSON AND CHARLES E. NEEDHAM, OF ALLENTOWN, PENNSYLVANIA,
ASSIGNORS TO BRADLEY PULVERIZER COMPANY, OF BOSTON, MASSACHUSETTS,
A CORPORATION OF MAINE.

GRINDING MILL.

Application filed November 16, 1921. Serial No. 515,509.

To all whom it may concern:

Be it known that we, WILLIAM A. GIBSON and CHARLES E. NEEDHAM, citizens of the United States, and residents of Allentown, county of Lehigh, State of Pennsylvania, have invented an Improvement in Grinding Mills, of which the following description, in connection with the accompanying drawing, is a specification, like characters on the drawing representing like parts.

This invention relates to improvements in centrifugal grinding mills of the general type illustrated in the patents to Edwin C. 15 Griffin, No. 769,740, granted September 13, 1904, and No. 1,175,436, granted March 14, 1916. In this type of grinding mill, the material to be ground is crushed against an annular grinding ring by the centrifugal 20 action of a plurality of rolls which are carried by shafts, which are pivotally mounted on a carrier, which is rotated by a central vertical roll actuating shaft.

In this type of mill as heretofore constructed the vertical roll actuating shaft has been directly driven by a large pulley secured to the upper portion of said shaft. This has required the use of a belt, the leads of which engaging the pulley are vertical 25 if driven from a vertical shaft, or are twisted if driven from a horizontal shaft.

One of the objects of the present invention is to provide an improved driving mechanism through which power may be transmitted by suitable gearing to the vertical roll actuating shaft from a horizontal driving shaft, which may be rotated either by a horizontal belt or may be directly connected conveniently to a suitable motor.

A further object of the invention is to provide a frame having a single supporting girder for sustaining the weight of the rotating parts and providing a journal for the vertical roll actuating shaft.

Another object of the invention consists in providing a single supporting girder of this type with suitable bearings for a driving shaft located at right angles to the axis of the vertical roll actuating shaft.

A further object of the invention is to provide a bevel gear drive for said vertical roll actuating shaft, in which means are

provided for maintaining the proper lubrication of the gears.

A further object of the invention consists in providing a novel bearing construction for the driving mechanism which supports the roll actuating shaft.

A further object of the invention is to provide an overhead drive for a grinding mill of this character which will be more accessible for purposes of repair or replacement than in former constructions.

Other objects and features of the invention will more fully appear from the following description and the accompanying drawings and will be pointed out in the claims.

A preferred embodiment of our invention is illustrated in the accompanying drawings as applied to a centrifugal grinding mill of the type generally illustrated in the Griffin patents above mentioned, and inasmuch as improvements to which this invention relates are not concerned with the grinding rolls which are operated by the vertical roll actuating shaft, this well known mechanism has not been illustrated in the accompanying drawings. It will, however, be understood that any usual type of centrifugal grinding mechanism operable from the vertical roll actuating shaft may be employed so far as the present invention is concerned.

In the drawings:

Fig. 1 is a side elevation of a centrifugal grinding mill, certain parts of the upper portion of the frame in the driving mechanism being illustrated in vertical section;

Fig. 2 is an end elevation of the grinding mill shown in Fig. 1, the driving shaft being shown in section, the pulley and outer bearing being omitted;

Fig. 3 is a vertical sectional view through the central portion of the upper girder of the machine illustrated in Fig. 1, showing the hub of the driving mechanism which supports the vertical roll actuating shaft in elevation, and illustrating the bearings and lubricating mechanism forming a part of the invention.

The centrifugal grinding machine to which the invention is applied comprises a base portion 1, which contains the grind-

ing ring and serves also as a base for supporting the superstructure of the mill, which carries the vertical roll actuating shaft, and the carrier which supports the 5 centrifugal actuated rolls which cooperate with the grinding ring. The present invention comprises a novel frame, which consists in pairs of preferably A-shaped standards 2 and braces 3, which are firmly secured at their lower ends between suitable lugs extending upwardly from the base 1, and at their upper ends are secured to and support saddles, 4, which carry a cross girder, which sustains the rotating parts of the 10 mill.

One of the principal features of the invention relates to the design of the frame construction, in which the central girder and its seat are so formed as to be readily 15 assembled and accurately adjusted to position properly the bearing for the vertical roll actuating shaft. This is accomplished in the preferred embodiment of the invention by providing the saddles 4, which are 20 supported on the standards, with concave, preferably semi-cylindrical, sockets 5, which are adapted to receive the turned end sections 6—7 of the cross girder 8. By reason of this construction, the ends of the cross 25 girder 8 can be readily dropped into the sockets 5 in said saddles, and secured therein by suitable fastenings such as bolts 9, extending down through the lower portions of said end sections and through the saddles.

30 The girder desirably is in the form of a slightly arched beam having a central, preferably enlarged, annular portion 10, with members 11 and 12 extending radially therefrom and terminating in the horizontal turned extensions 6—7 above described. The 35 central portion 10 of the upper girder is provided with an aperture 13, through which the central roll actuating shaft extends, and in which it is carried by the hub 40 of the driving mechanism, which is journaled in said aperture in a manner which will be hereinafter fully explained.

45 The member 12 of the upper girder 8 desirably is so constructed as to contain supports for the bearings of the driving shaft, and also preferably to provide a lubricant well for a pinion on said driving shaft, which drives a suitable gear for rotating the roll actuating shaft. In the construction 50 illustrated, the member 12 of the upper girder 8 is provided with bearing receiving recesses 14 and 15 extending lengthwise of the member 12, in which the bearings 16 and 17 of a driving shaft 18 are mounted. 55 The driving shaft 18 may be driven conveniently through a pulley 19 keyed upon said driving shaft.

60 Inasmuch as grinding mills of this character are usually very large, and require a large amount of power, a supplemental

bearing 20 desirably is provided for the free end of the driving shaft. Such a bearing may be conveniently supported upon a separate frame or pillar 21.

65 The vertical roll actuating shaft may be conveniently driven from the driving shaft through a pair or train of gears of well known type. As illustrated herein, the bevelled pinion 22, which is keyed to the driving shaft 18, engages the teeth of an annular bevelled ring 23, forming part of a gear 24, which is secured to and supports the roll actuating shaft, as will be herein-after more fully explained.

70 Preferably the portion 12 of the girder 8 is provided with a well 25, which forms an oil receptacle and also serves to enclose the lower portion of the pinion 22. By reason of this construction, the lower portion of the gear 22 is always caused to run in oil, 75 and the oil which is carried up by it will lubricate effectively the teeth 23 of the gear 24. A drip pan 26, preferably formed in two half sections to embrace the rotating mechanism, lies below the gear 24, and is 80 provided with an inclined bottom surface 26*, which delivers the excess of oil which drips from the gear back to the oil well 25. A suitable cover may be detachably 85 superimposed upon the drip pan, or other 90 supporting member, to form with the drip pan a chamber enclosing the gears and protecting them from dust and other foreign materials.

95 A thrust bearing 27 is desirably introduced between the end of the bevelled pinion 22 and the wall of the well 25, in order to prevent endwise movement of the shaft due to the component of force acting in the direction of the axis of the driving 100 shaft, resulting from the thrust between the teeth of the pinion 22 and those of the bevelled ring 23, which forms a part of the gear 24.

105 The gear 24 is provided with a hub which has an extension 28, which extends into the aperture 13 in the girder 8, and preferably projects a short distance through the lower end of said aperture.

110 The vertical roll actuating shaft extends upwardly through the centre of the gear hub, and is supported thereupon preferably by a wedge-shaped split nut 29 which is seated upon a complementary supporting member 30, which engages the upper end of the hub. The hub is supported upon anti-friction bearings carried by the cross girder 8.

115 In the preferred construction illustrated, an annular cup shaped member 31 is seated upon the upper end of the central portion 10 of the girder 8. This cup shaped member 31 is provided with a preferably spherically concave seat 32 for an aligning washer 33, the upper flat surface of which supports the 120

125 upper flat surface of which supports the 130

lower member 34 of a ball bearing. The upper section 35 of the ball bearing is seated in a groove in the gear hub 28, and supports the gear, and with it the vertical roll actuating shaft.

The cup shaped member 31 is so formed as to extend upwardly and surround the outer wall 36 of the groove in which the upper section 35 of the thrust bearing is seated. Thus the cup shaped member 31 provides a chamber to receive the oil which is fed into the thrust bearing in a manner hereinafter to be described, and also serves to exclude dust from the bearing for the vertical roll actuating shaft.

A bronze bushing 37 desirably is interposed between the hub extension 28 and the wall of the aperture 13, and extends from near the lower end of the hub extension upwardly, preferably to the level of the ball bearing which sustains the gear 24.

The lower end of the hub extension 28 projects below the central portion 10 of the transverse upper girder 8, and preferably is provided with an annular groove 38, which is engaged by a flange upon a sectional collar 39, which is clamped upon the lower end of said gear hub extension by a sleeve 40, which may be shrunk or otherwise clamped upon said collar. By reason of this construction the extension 28 of the hub is, in effect, provided with a flange underlying the central portion 10 of the upper girder 8 which will prevent the gear from riding up upon the pinion and slipping when the mill is operated under heavy power.

A preferred lubricating mechanism for the bearing of the hub 28 of the gear 24 is illustrated herein which comprises the invention disclosed in an application of Charles E. Needham, Serial Number 515,492 filed November 16, 1921.

In this preferred construction the lower end of the hub extension is enclosed in an oil chamber from which the oil is delivered by centrifugal force to the bearing and caused to creep up along the outer surface of the hub extension to the supporting thrust bearing, whence it is delivered into the cup shaped receptacle 31 and returned through a suitable duct into the oil chamber. As illustrated herein a receptacle 41 is secured to the under face of the central portion 10 of the girder 8 and is provided with a wall 42 which extends upwardly into a recess in the inner wall of the hub and closely adjacent to the shaft. This recess or chamber is of annular form and provided with an upwardly flaring outer wall 43, through the upper portion of which ports 44 extend to the bearing, so that oil may be delivered to the bearing between the periphery of the hub extension and the bushing 37. By reason of the fact that this hub extension projects into the oil in the oil

chamber 41, the centrifugal force of the rotating hub extension will cause the oil to creep up along the upwardly flaring wall of the recess and thence through the port or ports 44.

A plurality, preferably three ports, are provided through the wall of the hub extension, and these ports are adapted to communicate with the lower end of spiral grooves 45, which extend around the periphery of the hub in a direction to cause the oil entering them to ascend along the inner wall of the bushing 37. The oil will, therefore, be carried up between the hub and its bushing until discharged over the top of the bushing 37 into the receptacle 31, from which it is conducted through a suitable duct 45 back to the oil chamber 41. The duct 45 may be either formed by grooving the outer wall of the bronze bushing vertically, or by grooving or boring vertically through the central portion 10 of the cross girder. By reason of this construction a continuous circulation of oil may be maintained through the bearing, thus insuring proper lubrication of the bearing.

The cup shaped member 31 which encloses the thrust bearing, and the receptacle 41 which underlies the lower end of the bearing, effectively exclude dust from the bearing, and also prevent any dripping of the oil into the material which is being pulverized. This is very important as it is desirable to keep the product free from any oil.

By reason of the present invention the parts of a large and heavy grinding mill have been greatly simplified, and so designed that they can be readily and accurately assembled, and can be driven from any usual system of power transmission.

The special construction of the girder with its bearings for the counter-shaft and turned ends adapted to seat in the complementary sockets in the saddles of the frame, likewise is of great importance, as it enables the machine to be assembled more easily and more accurately, and also does away with a considerable amount of the superstructure heretofore employed in mills of this type.

By reason of the overhead arrangement of the gearing the gears, the driving shaft, and the bushings for all the bearings are rendered easily accessible and may be readily removed or replaced when worn without dismantling the grinding mechanism.

It will be understood that the preferred embodiment of the invention disclosed herein is of an illustrative character, and is not restrictive, and that various changes in form, construction and arrangement of parts may be made within the spirit and scope of the following claims.

Having thus described the invention, what

we claim as new, and desire to secure by Letters Patent, is:

1. In a centrifugal grinding mill having a grinding chamber, a vertical roll actuating shaft, a frame comprising standards located on opposite sides of said grinding chamber having girder receiving saddles, a girder having an aperture for said roll actuating shaft and sections complementary to said saddles adapted to be seated therein, and means for securing said girder sections rigidly to said saddles.
2. In a centrifugal grinding mill having a grinding chamber a vertical roll actuating shaft, a frame comprising standards located on opposite sides of said grinding chamber, girder receiving saddles carried by said standards, having semi-cylindrical sockets, a girder having an aperture for said roll actuating shaft and sections complementary to the girder receiving sockets, and means for securing said girder sections rigidly to said saddles.
3. In a centrifugal grinding mill having a grinding chamber a vertical roll actuating shaft, a frame comprising standards located on opposite sides of said grinding chamber, girder receiving saddles carried by said standards, a girder having an apertured portion providing a journal for said vertical actuating shaft, and members extending radially therefrom having end sections complementary to said saddles and aligned recesses for bearings in one of said radially extending members.
4. In a centrifugal grinding mill having a grinding chamber a vertical roll actuating shaft, a frame comprising standards located on opposite sides of said grinding chamber, girder receiving saddles carried by said standards, a girder having an apertured portion providing a journal for said vertical actuating shaft, members extending radially therefrom having end sections complementary to said saddles and aligned recesses for bearings in one of said radially extending members, and a well intermediate of the recesses for said bearings.
5. A girder for centrifugal grinding mills comprising a substantially central portion, having an aperture to receive a bearing for a roll actuating shaft and members extending radially from said central portion having cylindrical end portions, recesses for bearings in one of said members extending in radial relation to the axis of said aperture, and a well intermediate of said recesses.
6. In a centrifugal grinding mill having a vertical roll actuating shaft, a frame comprising standards having saddles provided with semi-cylindrical sockets and a girder having a substantially central portion provided with an aperture for said roll actuating shaft and members extending radially from said central portion having cylindrical end portions mounted in the sockets in said standards, a driving shaft mounted in bearings carried by one of said radially extending girder members and extending lengthwise thereof, a pinion on said driving shaft and a gear on said vertical roll actuating shaft engaging said pinion.
7. In a centrifugal grinding mill having a grinding chamber a vertical roll actuating shaft, a frame comprising standards located on diametrically opposite sides of said grinding chamber and a girder having a substantially central portion provided with an aperture for said roll actuating shaft, members extending radially from said central portion mounted on said standards, bearing receiving recesses in one of said radially extending girder members extending lengthwise thereof, bearings in said recesses, a driving shaft mounted in said bearings, a bevelled pinion on said driving shaft intermediate of said bearings, and a bevelled gear on said roll actuating shaft engaging said pinion.
8. In a centrifugal grinding mill having a grinding chamber a vertical roll actuating shaft, a frame comprising standards located on diametrically opposite sides of said grinding chamber and a girder having a substantially central portion provided with an aperture for said roll actuating shaft, members extending radially from said central portion mounted on said standards, bearing receiving recesses in one of said radially extending girder members extending lengthwise thereof, bearings in said recesses, a driving shaft mounted in said bearings, a bevelled pinion on said driving shaft intermediate of said bearings, a bevelled gear on said roll actuating shaft engaging said pinion, and an anti-friction thrust bearing acting upon said driving shaft to prevent endwise movement thereof.
9. In a centrifugal grinding mill having a grinding member a vertical roll actuating shaft, a frame comprising standards located on opposite sides of said grinding chamber, a girder having a substantially central portion provided with an aperture for said roll actuating shaft and members extending radially from said central portion mounted on said standards, bearing receiving recesses in one of said radially extending girder members extending lengthwise thereof, and a well in said member intermediate of said bearing recesses forming an oil receptacle, bearings in said bearing recesses, a driving shaft mounted in said bearings, a bevelled pinion on said driving shaft partially enclosed in said well, and a bevelled gear on said roll actuating shaft engaging said pinion.
10. In a centrifugal grinding mill having a grinding chamber a vertical roll actuating

- shaft, a frame comprising standards located on opposite sides of said grinding chamber, a girder having a substantially central portion provided with an aperture for said roll actuating shaft and members extending radially from said central portion mounted on said standards, bearing receiving recesses in one of said radially extending girder members extending lengthwise thereof, a well in said member intermediate of said bearing recesses, forming an oil receptacle, bearings in said bearing recesses, a driving shaft mounted in said bearings having a beveled pinion partially enclosed in said well, a beveled gear on said roll actuating shaft engaging said pinion, whereby the rotation of the pinion in the said oil receptacle will lubricate said pinion and the teeth of said gear, and a drip pan underlying said gear, having means for returning the oil deposited therein to said well.
11. In a centrifugal grinding mill having a vertical roll actuating shaft, a frame comprising an upper supporting girder having an aperture therethrough for said roll actuating shaft, driving means supporting said shaft, having a hub embracing said shaft journalled in said aperture having its end portion projecting downwardly through said girder and an anti-friction thrust bearing, mounted on said girder, supporting said driving means.
12. In a centrifugal grinding mill having a vertical roll actuating shaft, a frame comprising an upper supporting girder having
- an aperture therethrough for said roll actuating shaft, driving means supporting said shaft, having a hub embracing said shaft journalled in said aperture, an anti-friction thrust bearing, mounted on said girder, supporting said driving means, and co-operating flanges on said girder and gear forming an oil chamber for said thrust bearing and acting to exclude dust therefrom.
13. In a centrifugal grinding mill having a vertical roll actuating shaft, a frame comprising an upper supporting girder having an aperture therethrough for said roll actuating shaft, a driving means supporting said shaft, having a hub journalled in said aperture and projecting therethrough, and a retaining collar on the projecting end of said hub adapted to prevent upward movement of said hub in its journal.
14. In a centrifugal grinding mill having a vertical roll actuating shaft, a frame comprising an upper supporting girder having an aperture therethrough for said roll actuating shaft, a driving means supporting said shaft, having a hub journalled in said aperture and projecting therethrough, an annular recess in the projecting end of said hub, a split collar having a flange engaging said recess, and a clamping sleeve surrounding said collar.

In testimony whereof, we have signed our names to this specification.

WILLIAM A. GIBSON.
CHARLES E. NEEDHAM.
